UNITED STATES PATENT OFFICE

EMIL HENRIK WIDEGREN AND KLAS AUGUST WIDEGREN, OF ALBY, SWEDEN.

TRANSMITTER FOR ELECTRIC WRITING-TELEGRAPHS.

1,154,279.

Specification of Letters Patent. Patented Sept. 21, 1915.

Application filed December 20, 1913. Serial No. 807,916.

To all whom it may concern:

Be it known that we, EMIL HENRIK WIDEGREN and KLAS AUGUST WIDEGREN, subjects of the King of Sweden, and both residents 5 of Alby, Sweden, have invented new and useful Improvements in Transmitters for Electric Writing-Telegraphs, of which the following is a specification.

Our invention relates to electric writing 10 telegraphs which are actuated by pulsating currents generated by means of a continuously rotating commutator along which one or more brushes may be moved. Such an apparatus is for instance described in our 15 U. S. Patent No. 1054811. In order that such apparatus shall work satisfactory, it is necessary that the movements of the current collecting brush or brushes take place in strict correspondence with the movements of 20 the writing pen of the transmitter. By means of the devices heretofore used for transmitting movements from the writing pen to the brushes no such strict correspondence has been attained, and on account 25 thereof, the writing in the receiver has been uneven and distorted so that it does not render distinctly the handwriting put down in the transmitter, as is to be desired in apparatus of this kind.

Our invention relates to a simple device 30 for transmitting movements from the writing pen of the transmitter to the current collecting brush or brushes of the commutator by which invention back-lash or other 35 irregularities in the movements of the brush relative to the writing pen are obviated as far as possible. The invention consists, chiefly, in this that the current collecting brush bearing against the commutator is 40 pivoted on a center and by means of a connecting rod or arm connected to the writing pen of the transmitter.

Two different forms of the invention are 45 illustrated in the accompanying drawing in which Figure 1 shows a plan view of one form, while Fig. 2 shows a plan view and Fig. 3 a side view of the other form. The parts of the transmitter shown in the drawing are those relating to the present invention, while other parts, especially the diagram of the connections, are omitted for the sake of simpleness.

Relating to Fig. 1, 1, 2 designate a double 50 commutator roller connected, by means of suitable circuit connections (not shown on the drawing) to a source of continuous elec-

tric current. Bearing against each of the rollers 1 and 2 is a sliding brush 3 and 4 respectively supported by an arm 7 and 8 respectively which is pivoted on a center 5 and 6 respectively. Rigidly connected with the arms 7 and 8 are other arms 9 and 10 respectively connected by means of rods 11 and 12 to the writing pen 13 of the transmitter. On moving the writing pen across the writing plane 14 the arms 7, 9 and 8, 10 are turned about their centers 5 and 6 respectively, and the brushes are, on account thereof, moved along the rollers 1 and 2. Since in this arrangement for transmitting movements from the writing pen to the sliding brushes joints occur at the rods 11 and 12 only which joints without any difficulty can be effected without back-lash, it is attained that the brushes may be brought to follow the movements of the writing pen with necessary exactness.

The form shown in Figs. 2 and 3 differs from that shown in Fig. 1 only in this that the brushes 3 and 4 bear against the upper side and the lower side respectively of the same commutator roller 15. The pivots 5 and 6 of the brush arms 7, 9 and 8, 10 are located at each side of the commutator roller, and the writing plane 14 is placed above the roller 15. In other respects, the device for transmitting movements from the writing pen 13 to the brushes 3 and 4 corresponds to that shown in Fig. 1.

Having now described our invention, what we claim as new and desire to secure by Letters Patent is:

1. A transmitter for electric writing telegraphs including a rotary commutator adapted to emit pulsating currents, a brush bearing on said commutator, a holder carrying said brush, said holder being arranged to swing in a plane essentially parallel to the axis of the commutator, a hand operated writing pen, and a mechanical connection between the pen and the said holder.

2. A transmitter for electric writing telegraphs, including a rotary commutator adapted to emit pulsating currents, brushes bearing on each side of said commutator, a holder for each of said brushes, said holders being arranged to swing in planes essentially parallel to the axis of the commutator, a hand operated writing pen, and mechanical connections between the pen and the said holders.

3. A transmitter for electric writing tele-

graphs, including a rotary commutator having curve-shaped commutator bars, a brush bearing on said commutator, a holder carrying said brush, said holder being arranged 5 to swing in a plane essentially parallel to the axis of the commutator, a hand operated writing pen, and a mechanical connection between the pen and the said holder.

4. A transmitter for electric writing tele-
10 graphs including a table, a pen movable on said table, a rotary commutator, brushes bearing on said commutator, holders carrying said brushes, said holders being ar-

ranged to swing in a plane essentially parallel to the axis of the commutator, and 15 mechanical connections between the pen and the said holders.

In testimony that we claim the foregoing as our invention, we have signed our names in presence of two subscribing witnesses.

EMIL HENRIK WIDEGREN.
KLAS AUGUST WIDEGREN.
